UNITED STATES PATENT OFFICE.

EDWARD H. SCHANE, OF YOUNGSTOWN, OHIO.

REEL.

Application filed December 21, 1921. Serial No. 523,851.

To all whom it may concern:

Be it known that I, EDWARD H. SCHANE, a citizen of the United States, residing at Youngstown, in the county of Mahoning and State of Ohio, have invented a new and useful Improvement in Reels, of which the following is a full, clear, and exact description.

The present invention relates broadly to 10 winding and reeling, and more particularly to a reel for plain or barbed wire and similar materials, although it is adapted to other uses, as will be readily apparent.

The invention relates to reels of the general type disclosed in the patent to Charles I. Dailey No. 1,259,725 of Mar. 19, 1918, but is adapted to provide a readily collapsible reel, the parts of which may be more inexpensively and expeditiously produced and 20 readily assembled or dis-assembled as desired, and embodies several of the features illustrated and claimed in my co-pending application Serial No. 523,850, filed Dec. 21, 1921.

25 The general nature of my invention, together with its objects and advantages will be readily apparent from the accompanying drawings forming part of this specification and illustrating a preferred embodiment of 30 my invention, it being premised that changes may be made in the construction and arrangement of parts within the scope of the appended claims, without departing from the spirit of the invention.

35 In the drawings,—

Figure 1 is a perspective view of a reel constructed in accordance with the present invention;

Figure 2 is a side elevation of a slightly 40 modified form of reel, partly broken away;

Figure 3 is an end elevation of the reel 45 illustrated in Figure 2;

Figure 4 is a plan view of one of the head members;

Figure 5 is a plan view of one of the cage 50 barrel members;

Figure 6 is an end view of the construction illustrated in Figure 5;

Figure 7 is a plan view of the other cage 55 barrel member; and

Figure 8 is an end view of the construction illustrated in Figure 7.

As shown in the drawings, a reel constructed in accordance with the present in-

vention comprises a cage barrel member A 55 of generally rectangular formation and a dissimilar, substantially rectangular cage barrel member B. The two cage barrel members are adapted to be assembled to form a cage barrel for receiving the material to be wound thereon. The member A comprises side portions 1 and connecting end portions 2. In like manner, the member B comprises side portions 3 and end portions 4. The side portions 1 and 3 are adapted to have the wire 60 or other material wound therearound, while each of the end portions 2 and 4 are offset intermediate their ends to form half bearings 5. All of the side portions are of substantially the same length, but the end portions 4 lie slightly below the ends of the side portions of the member B, whereby projections 6 are provided adjacent each corner of the member B.

Adapted to cooperate with the cage barrel members A and B, are two similar heads C of generally cross-shaped construction. Each of the heads C comprises four substantially uniform loops 8 each spaced substantially 70 90° from the adjoining loops. The 80 sides of the loops intersect to form seats 9 which are also substantially uniformly spaced both circumferentially and radially.

In assembling, a cage barrel member B is placed within a cage barrel member A so that 85 the end portions 2 and 4 extend at substantially right angles to each other, and diagonally of the cage barrel. In this position, the half bearings 5 cooperate to form a center bearing at each end of the cage barrel 90 for the reception of a rod or bar, not shown, forming a rotatable support for the reel during winding and unwinding. A head C is then slipped through the cage barrel member A with two of its loops on each side thereof, 95 and then forced upwardly into the position illustrated in Figure 1 to bring the two diagonally opposite seats 9 thereof into engagement with the intersections of the side and end portions of the member A. Thereafter, it is sprung over the projections 6 to bring the other two seats 9 within the same. The other head is then inserted in position and the reel is ready for use.

In the completed reel, the end portions 2 105 and 4 all serve as tension members, and the heads serve as compression members, whereby the members are all held firmly in posi-

tion without any intertwisting of any of the members. At the same time, the cage barrel member A serves as a tension member, tending to prevent the heads C from moving outwardly in a direction parallel to the longitudinal axis of the cage barrel, and the cage barrel member B serves as a compression member tending to prevent the heads from moving inwardly along said axis, whereby a light, rigid structure comprising a minimum amount of wire is provided.

As the heads C are all in one piece, each lies in a single plane, presenting a smooth winding surface to the cage barrel. Also, due to the fact that the side portions of the cage barrel members are of substantially the same length, the ends of the projections 6 and the end portions 2 lie in the same transverse plane, permitting the reel to be firmly stood on end.

In some cases, it is desirable to reinforce the cage barrels to prevent bending of the side portions during the winding operation. This may be effectively accomplished by forming each of the side portions at some point intermediate its length with a small bend 10, and forcing a ring 11 into engagement with all of these bends. As the ring 11 serves entirely as a compression member, it will be obvious that it may either have its ends united or loosely abutting.

The advantages of the present invention arise from the provision of a reel readily assembled or dis-assembled, and held in assembled position solely by heads which are securely held against movement in any direction parallel to the longitudinal axis of the reel.

40 I claim:

1. A reel, comprising a cage barrel and opposite heads, the cage barrel comprising a pair of dissimilar members having their end portions disposed diagonally thereof, whereby opposite sides of said members form diagonally opposite corners of said barrel, substantially as described.

2. A reel, comprising a cage barrel and opposite heads, the cage barrel comprising two members each having end portions adapted to extend one over the other in axially spaced relationship and receive a head in the space provided therebetween with said portions on opposite sides of the head, substantially as described.

3. A reel, comprising a cage barrel and opposite heads, the cage barrel comprising two members each having end portions adapted to extend one over the other in axially spaced relationship and receive a head in the space provided therebetween with said portions on opposite sides of the head, one of said portions preventing movement of the head in one direction parallel to the axis of the cage barrel, and the other of

said portions preventing movement of the head in the opposite direction, substantially as described.

4. A reel, comprising a cage barrel member having side portions and end portions, said end portions extending between the side portions below the ends thereof, a second cage barrel member having side portions and end portions, said last mentioned end portions extending between the side portions in substantially the plane of the ends thereof, and heads supported outside of said first mentioned end portions and inside of said last mentioned end portions, substantially as described.

5. A reel, comprising a cage barrel member having side portions and end portions, said end portions extending between the side portions below the ends thereof, a second cage barrel member having side portions and end portions, said last mentioned end portions extending between the side portions in substantially the plane of the ends thereof, and one-piece heads supported outside of said first mentioned end portions and inside of said last mentioned end portions, substantially as described.

6. A collapsible reel, comprising a cage barrel and opposite heads, the cage barrel comprising a pair of interfitting dissimilar members prevented from collapsing in every direction at right angles to the axis of rotation of the barrel entirely by said heads, substantially as described.

7. A reel, comprising a cage barrel, opposite heads, the cage barrel comprising a pair of dissimilar members having their end portions disposed diagonally thereof, and means for reinforcing said cage barrel, substantially as described.

8. A reel, comprising a cage barrel, opposite heads, the cage barrel comprising two members each having end portions adapted to extend one over the other in axially spaced relationship and receive a head in the space provided therebetween with said portions on opposite sides of the head, and means for reinforcing said cage barrel, substantially as described.

9. A reel, comprising a cage barrel, opposite heads, the cage barrel comprising two members each having end portions adapted to extend one over the other and receive a head therebetween, one of said members preventing movement of the head in one direction parallel to the axis of the cage barrel, and the other of said members preventing movement of the head in the opposite direction, and means for reinforcing said cage barrel, substantially as described.

10. A reel, comprising a cage barrel member having side portions and end portions, said end portions extending between the side portions below the ends thereof, a second cage barrel member having side por-

- tions and end portions, said last mentioned end portions extending between the side portions in substantially the plane of the ends thereof, heads supported outside of 5 said first mentioned end portions and inside of said last mentioned end portions, and means for reinforcing said cage barrel members, substantially as described.
11. A reel, comprising a cage barrel member having side portions and end portions, 10 said end portions extending between the side portions below the ends thereof, a second cage barrel member having side portions and end portions, said last mentioned end portions extending between the side portions in substantially the plane of the ends thereof, one-piece heads supported outside of said first mentioned end portions and inside of said last mentioned end portions, and 15 20 means for reinforcing said cage barrel members, substantially as described.
12. A collapsible reel, comprising a cage barrel, opposite heads, the cage barrel com-
- prising a pair of dissimilar members prevented from collapsing entirely by said heads, and means for reinforcing said cage barrel, substantially as described. 25
13. A collapsible reel, comprising a cage barrel, opposite one-piece heads, the cage barrel comprising a pair of dissimilar members prevented from collapsing entirely by said heads, and means for reinforcing said cage barrel, substantially as described. 30
14. A reel, comprising a cage barrel and opposite heads, the cage barrel comprising 35 a pair of dissimilar members having their end portions disposed diagonally thereof, each of said heads lying within one of said members, and the other of said members having means engaging and preventing lateral movement of the head, substantially as described. 40

In testimony whereof I have hereunto set my hand.

EDWARD H. SCHANE.
